LOOSE-LEAF BINDER

Clarence W. Vogt, Norwalk, Conn., and Eino E. Lakso, Fitchburg, Mass.; said Lakso assignor to said Vogt

Application January 21, 1939, Serial No. 252,106

22 Claims. (Cl. 129—13)

It has been proposed to provide a loose leaf binder with two pivotally supported opposed rows of sheet retaining prongs, movable endwise in opposite directions across the back, to afford extra room at the inner edges of the prong retained sheets in open position of the binder. This permits the sheets to lie flatter for easy reference, and permits said sheets to be separated into two batches for retention on the two rows of prongs respectively. This separation allows the prongs to be swung into upright position with respect to the open covers for removal or insertion of the sheets.

With a binder of this construction, if the covers are inadvertently or accidentally closed before the prongs are restored to normal position across the back of said binder, the sheets retained in the upstanding prongs are apt to be torn or otherwise damaged, and the mechanism guiding the prongs in their endwise expanding movement unduly stressed.

One object of the present invention is to provide means for locking the covers in open position, while the prongs are in upright position with respect to their respective covers. Thus the back and covers form a rigid or stiff support, so that the binder may be carried from place to place, held in the lap, or otherwise supported or handled without danger or injury to the sheets.

Another object is to provide locking means of the type above referred to, which is automatically released when the upstanding prongs are swung across the back of the binder in the same plane, to permit the covers to be closed.

Another object is to provide means for connecting the two opposed rows of prongs for simultaneous correlated swinging movement, so that pivotal manipulation of one row of prongs will cause corresponding pivotal movement of the other row.

As a feature of the present invention, the above objectives are attained, without interfering with the opening or closing movement of either cover independently of the other, while the prongs extend across the back.

Another object is to provide new and improved means for securing various fixed metal parts of the mechanisms above referred to to the enclosing casing of the binder.

Various other objects, features and advantages of the invention will be apparent from the following description of merely one embodiment of the invention, and from an inspection of the accompanying drawings, in which:

Fig. 1 is a perspective of a form of binder, 55

embodimenting our invention, and shown without the binding, and with one cover in open position,

Fig. 2 is an elevation of the binder with both covers in open position,

Fig. 3 is an inside face view of the empty binder in open position, with the prongs locked across the back, the binding being eliminated for the sake of clarity.

10 Fig. 4 is an enlargement of the central portion of the view shown in Fig. 3,

Fig. 5 is a section taken on line 5—5 of Fig. 4,

Fig. 6 is a section similar to that of Fig. 5 but showing the prongs in intermediate pivotal position,

Fig. 7 is a section similar to that of Fig. 5, but showing the prongs in upstanding position with respect to the open covers of the binder,

15 Fig. 8 is a section similar to that of Fig. 5, but showing the covers in closed position,

Fig. 9 is a section taken on line 9—9 of Fig. 4, but on a larger scale,

Fig. 10 is a section similar to that of Fig. 9, but showing the prong locking means released to permit the prongs to be swung into upright position with respect to their open covers,

Fig. 11 is a section taken on line 11—11 of Fig. 4,

30 Fig. 12 is a perspective of the hinge slide, forming part of the means for locking the binder in open position,

Fig. 13 is a perspective of the toggle lever forming part of the mechanism of the present invention,

35 Fig. 14 is a perspective of the toggle bracket, forming part of the mechanism of the present invention,

Fig. 15 is an inside view of the opened empty binder, showing the binding with certain fixed

40 parts of its mechanisms secured thereto,

Figs. 16, 17, 18 and 19 are sections taken on lines 16—16, 17—17, 18—18 and 19—19 of Fig. 15 respectively, but shown on a larger scale, and

45 Fig. 20 is an enlargement of part of the section of Fig. 19.

In the specific form of the invention shown, the binder includes a flat rigid non-bendable back 10, desirably of comparatively thick cardboard, and a pair of covers 11, also desirably of 50 thick cardboard, and hinged to the respective side edges of said back as shown in Figs. 15, 16 and 17, and as will be hereinafter described. These covers 11 are adapted in closed position of the binder to extend at right angles to the back 10 as shown in Fig. 8, and in open position to ex-

tend substantially in the plane thereof as shown in Figs. 2, 5, 6 and 7.

The binding forming the facings for the back 10 and the covers 11, and the hinge connections between said back and said covers are not shown in Figs. 1 to 11 for the sake of clarity, but are shown in Figs. 15 to 20.

Pivotedly carried respectively by the covers 11 is a pair of parallel prong holders or frames 14 (Figs. 1 to 11), each having a longitudinal angle bar section 15, and a pair of end flanges 16, extending transversely thereof, and pivotedly connected at 17 to the inner sides of brackets 18 respectively. Each bracket 18 extends transversely of and is rigidly connected to its respective cover 11, and for that purpose has a base flange 20, seated on said cover and affixed thereto in a manner to be hereinafter described.

Affixed to the leg 15a of each frame bar 15 is a row of parallel straight sheet retaining prongs 23 of equal length, two in each row being shown, extending transversely of said leg, and staggered with respect to and overlapping the prongs 23 of the opposed row connected to the other frame bar 15.

If desired, a pair of aligned short prongs 24 may be affixed to the centers of the bars 15 respectively, these prongs being parallel to and in the same plane as the prongs 23, and being of such length that they do not overlap in closed position of the binder.

The length of the prongs 23 is such, that when the covers 11 are in closed position as shown in Fig. 8, each of these prongs will extend almost the full distance between the covers. In this closed position, the bar legs 15a will face each other, and will be closely adjacent to their respective covers 11, while the prongs 23 and 24 will lie in a single plane parallel to the back 10. Also in this position of the binder, the brackets 18 will have their pivotal mountings 17 spaced inwardly from the side edges of the back 10 as shown.

As the covers 11 are swung into open position, they will carry the brackets 18 with them, thereby causing their pivotal mountings 17 to move outwardly from the side edges of the back 10, until said covers are in the plane of said back as shown in Fig. 5. As these pivotal mountings 17 are moved outwardly from their original positions shown in Fig. 8, they will carry the prong frames 14 outwardly with respect to the side edges of the back 10, thereby causing transverse movement of said frames apart, and corresponding separating movement of the two rows of prongs. This operation is not sufficient to move the two rows of prongs 23 beyond overlapping relationship, so that while these prongs are held downwardly in a single plane parallel to the back 10, the sheets will be retained on said prongs and can be turned between the covers.

As a feature of the present invention, the two prong frames 14 are inter-connected for correlated simultaneous swinging movement from the position shown in Fig. 5, with the prongs 23 and 24 extending across the back to an upstanding position with respect to the covers as shown in Fig. 7. For that purpose, each of the prong frames 14 has a lug 30 near the center thereof, inclined inwardly towards the base 10 at an angle of about 45° with said base, when the prongs extend across the back in the position shown in Fig. 5. Pivotedly connected to the outer side of this lug 30 by means of a pivot pin 31 is a hinge leaf 32, having a pintle hinge connection 33 with the outer end of a connector bar 34. The con-

nection 33 extends at about 45° with the inner edge of its respective frame bar 15, to form a miter hinge connection between the corresponding bar 34 and hinge leaf 32. The inner end 5 section of each connector bar 34 slides in a guide 35, which in the specific form shown comprises two channel members 36, secured together back to back by soldering or the like, and slidably receiving the two opposed connector bars 34 respectively. The common center line of the two pivot pins 31 is desirably in the medial plane of the binder, and the two connector bars 34 are offset from opposite sides of the hinge connections 33 as shown in Figs. 3 and 4, to position these bars in exact alignment with their respective guide channels 36.

As the result of the miter hinge connections 33 between the connector bars 34 and the hinge leaves 32, a swinging movement of either one of the prong frames 14 about its pivotal mountings 17 will cause a turning of its respective connector bar about a longitudinal axis, and the slide movement of said bar in the guide 35. This turning action is transmitted to the guide 35, and in turn 20 to the other connector bar 34, to cause swinging movement of the other prong frame 14 about its pivotal mountings 17 in unison with the one being manipulated. This turning movement of the connector bars 34 with their guide 35 is indicated in Figs. 5, 6 and 7, illustrating the down, intermediate and upstanding positions respectively of the prongs 23 and 24.

In order to hold the guide 35 against sagging and against endwise movement without interfering with the turning movement thereof, there is provided a brace plate 37, having at one end on opposite sides thereof a pair of lugs 38, extending loosely into a pair of hooks or eyelets 40 respectively, formed near the middle of the rear side of a gib plate 41, fixed to the inner face of the back 10 in a manner hereinafter to be described. At the other end, the brace plate 37 is similarly provided with a pair of lugs 42, extending loosely in a pair of hooks or eyelets 43, which are 25 formed in an angle clip 44, soldered or otherwise secured to the inner rear corner of the guide 35 as shown in Figs. 4, 9 and 10. The hinge connections at the ends of the brace plate 37 formed by this construction permit free turning of the 30 guide 35, resulting from swinging movement of the prong frames 14 about their pivotal supports 17.

As the covers 11 are moved from a closed to an open position, the sheets A are flattened out as 35 shown in Fig. 2, causing them to apply a leverage to the prongs 23 and 24, tending to swing them upwardly about their pivotal supports into the position shown in Fig. 7.

Releasable means are provided for holding the 40 prongs 23 and 24 in a single plane parallel to the back 10, and to confine the movement of said prongs endwise as the binder is opened and closed. In the specific form shown this holding means comprises a lever 50 in the form of a plate, having its forward section of substantial width, and its rear section desirably of reduced width. This lever 50 is fulcrumed near its rear section for angular movement, and for that purpose, a plate 51, partially extending in an opening 52 in the 45 gib plate 41, and fixed to said gib plate by any suitable means such as rivets 53, has a pair of hooks 54 at the sides of its rear end, folded loosely over the shoulders 55 on said plate to form a pivot support therefor. The lever 50 has struck out therefrom a tab 56, from which a

tongue 57 is cut out and bent rearwardly from the plane thereof to form a detent. This detent 57 cooperates with a lock lug 58, in the form of an angle piece, secured to and embracing the forward inner corner of the guide 35, and having a forwardly extending lip 60, underlying the detent 57 in raised position of the lever 50 as shown in Fig. 9. In this position, the prongs 23 and 24 will extend in a single plane parallel to the back, and since the guide 35 is held against turning or outward movement by the abutment of the locking lip 60 against the inner edge of the detent 57, these prongs will be locked in this parallel position during their endwise movement.

When the lever 50 is angularly depressed into the position shown in Fig. 10, the detent 57 is moved out of engagement with the locking lip 60, thereby permitting swinging movement of the prongs 23 and 24 from the down position shown in Fig. 5 to upstanding position shown in Fig. 7.

As a feature of the present invention, the lever 50 has a snap action between the two extreme positions shown in Figs. 9 and 10 respectively, so that said lever will be retained in either one of said positions until it has been changed over to the other extreme position. For that purpose, the lever 50 forms part of a toggle, comprising a toggle link 65, having its forward edge pivotally retained in a pair of spaced channels 66 formed in a bracket 67, integral with the plate 51.

The rectangular opening 68 in the lever 50, formed by the bending of the tab 56 out of the plane thereof is approximately the shape of the toggle link 65, but slightly larger to permit free passage of said link therethrough, and the section 70 of said lever between the rear edge 71 of said opening and the hook engaged shoulders 55 of said lever, constitutes the other toggle link. The rear edge 72 of the toggle link 65 is square cut, and butt joined to the forward edge 71 of the toggle link 70, which is also square cut, so that said links are held in edge alignment during toggle action.

In order to assure against relative edge displacement of the two toggle links 65 and 70, the forward edge of the link 70 is upset to form two spaced ears 73, which are offset inwardly to underlie the rear edge of the link 65, while the rear edge of the latter link is similarly offset near its midle to form an ear 74, offset inwardly and underlying the forward edge of the link 70, as shown in Figs. 4, 9, 10 and 13.

In the position shown in Fig. 9, with the lever 50 elevated, and the prongs 23 and 24 locked across the back 10, the angle between the inner or lower sides of the two toggle links 65 and 70 is less than 180°. As the lever is depressed towards the position shown in Fig. 10, the two links 65 and 70 are forced towards co-planar relationship against yielding resistance of their pivotal supports. After these links 65 and 70 reach slightly beyond this co-planar position, they will automatically snap into reverse angular relationship. In this position, the angle between the inner sides of the toggle links 65 and 70 is more than 180° as shown in Fig. 10. The opening 68 in the lever 50 permits said lever to be slipped over the toggle link 65 without interference, during the angular movement of said lever.

As a feature of the present invention, when the prongs 23 and 24 are swung from upright position shown in Fig. 7 to down position shown in Fig. 5, the depressed lever 50 is automatically snapped into elevated position shown in Fig. 9, and said prongs locked in said position for endwise move-

ment. For that purpose, the rear end of the lever 50 has an outwardly and rearwardly inclined section 80 beyond the shoulders 55, terminating at its rear end in an inwardly and rearwardly inclined apron 81, and having a tongue 82, struck out therefrom and extending outwardly to form a detent. The rear end of the angle piece 58 has an inwardly and rearwardly inclined lip 83, adapted to press against the lever section 80 as the prongs 23 and 24 are swung downwardly across the back 10, from the position of the guide 35 shown in dotted lines in Fig. 10 to the position shown in full. This pressing movement of the lip 83 against the lever section 80, causes the angular elevation of the lever 50 to its original position shown in Fig. 9, in which position the prongs 23 and 24 will be locked for endwise movement upon opening and closing of the binder in the manner already described. The inward movement of the prongs 23 and 24 beyond the parallel position shown in Fig. 5 is prevented by the engagement of the lip 83 with the detent 82, and the abutment of the rear edge of the apron 81 against the gib plate 41, as shown in Fig. 9.

As another feature of the present invention, means are provided for locking the binder in open position while the prongs 23 and 24 are in upright position with respect to their respective covers. In the specific form shown, this locking means comprises a pair of opposed slides 90, hinged at their outer ends to the inner edges of the frame bars 15 respectively, and guided for slide movement in the gib plate 41. The hinge connection between each slide 90 and its corresponding frame bar 15 comprises a pair of spaced pintle engaging sections 91, desirably formed integral with the inner edge of the bar, and mating respectively with a pair of pintle engaging sections 92 at the outer end of said slide to embrace pintles 93. These pintles 93 are in axial alignment with the pivotal mountings 17 of their respective prong frame 14, so that said frame is free to swing about said mountings without interference from the slides 90.

The slides 90 are desirably formed of sheet metal, with the base section 95 adapted to be guided over the gib plate 41, and a pair of spaced hinge leaves 96, extending obliquely upwardly and outwardly from said base section, and terminating at their outer ends in the hinge sections 92 as shown in Fig. 12. In order to retain these slides 90 for slide movement over the gib plate 41, the side edges of said plate are reversely bent inwardly to form guide channels 97 for the corresponding side edges of said slides.

The transverse movement of the prong frames 14, resulting from the opening or closing of the covers 11 as above described, is transmitted to the slides 90, so that the latter move over the gib plate 41.

The swinging movement of the covers 11 into open or closed position causes angular movement of the brackets 18, and corresponding angular movement of the pivotal mountings 17. If fixed, unyielding hinge connections were provided between the covers 11 and the back 10, this angular movement of the pivotal mountings 17 would unduly stress the slides 90, and is apt to jam them in the gib plate 41. However, in the specific form shown, the hinge connections between the covers 11 and the back 10 are flexible, and formed by the fabric binding, as shown in Figs. 15, 16 and 17 and as will be hereinafter described, to permit relative displacement of the hinge edges of said

covers out of opposed registry. This construction causes the hinge connections to give or yield as the covers 11 are opened or closed, so that no undesirable stress is transmitted to the slides 90 as the result of this movement.

If the hinge connection between the covers 11 and the back 10 is of the piano or other rigid type, the angular movement of the pivotal mountings 17 can be compensated for by making these mountings of the slide type, as described in our co-pending application Serial No. 240,492, filed November 15, 1938.

Each slide 90 is provided near its forward section with an upstanding flange 98, which is just high enough to ride underneath the raised lever 50, during opening or closing movements of the covers. The lengths of the slides 90 are such, that in open position of the binder shown in Figs. 3 to 7, the inner edges 100 of their flanges 98 are spaced outwardly a short distance from the corresponding side edges 101 of the lever 50. This spacing of the inner edges of the two slides 90 in open position of the covers 11 permits the lever 50 to be depressed to the position shown in Fig. 10. The depressed lever 50, being in the path of slide travel of the flanges 98, acts as a lock for positively preventing closing of the covers 11. In this position, the covers 11 can only be closed after the lever 50 has been automatically snapped into elevated position shown in Fig. 9 by the swinging of the prongs 23 and 24 across the back 10. In this position, the flanges 98 are free to slide underneath the lever 50, so that the covers may be closed without interference.

In Figs. 15 to 20 is shown our new and improved means for binding the back 10 and covers 11, and for securing thereto various fixed parts of the mechanisms above described, without resort to the usual tongue and slot connections, which cut into the binding, and which interfere with effective passage of the blank binder through the usual glue applying or pressure rolls during binding operations.

For securing each bracket 18 to the inner side of its respective cover 11, the base 20 of said bracket has a pair of cylindrical flanges 109 (Figs. 15, 19 and 20), extending snugly about half way into corresponding holes 110 in said cover, and terminating in radially inwardly extending annular rims 111 respectively. On the outer face of the covers 11, opposite each of the bracket bases 20 is a binding plate 112, provided with a pair of cylindrical flanges 113, each extending in its corresponding hole 110 with a snug fit, and terminating in an annular radial rib 114, the outer edge section 115 of which is spun or otherwise crimped over the corresponding rim 111 of the bracket base 20.

The gib plate 41 is similarly secured to the inner face of the back 10, and for that purpose it has a pair of cylindrical flanges 116, extending snugly into corresponding holes 117 in said back, and terminating in radial inwardly extending annular rims 118 respectively. On the outer face of the back 10 opposite the gib plate 41 is a binding plate 119, having a pair of cylindrical flanges 120, each extending in its corresponding cover hole 117 with a snug fit, and terminating in a rim 121, spun or otherwise crimped over the corresponding rim 118 of said gib plate.

For binding operation, the binding plates 112 and 119 are first applied to the bare outer faces of their respective boards 10 and 11, and held thereon by the frictional retention of the cylindrical flanges 113 and 120 in the holes 110 and

117 of said boards. In order to present a continuous surface on the outer face of the covers 11, there is glued onto the bare face of each of said covers a filler sheet of paper 123, substantially the same thickness as that of the binding plate 112, and having cut-outs to receive said plates. Similarly glued to the outer bare face of the back 10 is a filler sheet of paper 124, substantially the same thickness as that of the binding plate 119, and having cut-outs to receive said plate. Over the continuous surface formed by these filler sheets 123 and 124 and the binding plates 112 and 119 is glued an outer flexible facing sheet 125 of suitable binding material such as "Fabrikoid." This facing sheet 125 is made to extend loosely across the hinge gaps 126 between adjoining side edges of the back 10 and the covers 11, and its border section 127 is folded over and adhesively secured to the inner face of said back and covers.

Over the inner bare face of the back 10 and over the inner edge sections of the covers 11 is adhesively secured a flexible facing sheet 130 of suitable binding material. This sheet 130 extends with slack across the hinge gaps 126, the loose sections of the two facing sheets 125 and 130 in said gaps being adhesively secured together at 131 as shown in Figs. 16 and 17, to form loose hinge connections. As already described, these loose hinge connections permit limited yield of the covers 11 out of edge registry with the back 10, for the purpose of confining the movement of the prong frames 14 to a translatory one during opening and closing of the binder.

The portions of the inner faces of the covers 11 between the facing sheet 130 and the border sections 127 of the facing sheets 125, are covered with sheets 132 of binding material.

The adhesive application of the facing sheets 125, 130 and 132 as described is accomplished efficiently and expeditiously, since there are no projecting parts which interfere with free passage of the blank binder throughout glue or pressure applying rollers.

The binder formed as described is usually made in a bindery, and then shipped to the plant where the operating mechanisms above described are mounted. The elimination of all projecting parts in the binders as formed in the bindery, permits these binders to be easily stacked for shipment to the assembling plant.

At the assembling plant, the brackets 18 and the gib plate 41 are mounted over the facing sheet 130, with their respective cylindrical flanges 109 and 116 passing through apertures in said sheet, and into the holes 110 and 117 of the covers 11 and back 10. At this phase of the assembling operation, the edge sections of the rims 114 and 121 of the binding plates 112 and 119 are cylindrical, so that they serve as centering means for the flanges 109 and 116 of the brackets 18 and gib plate 41. After these brackets 18 and gib plate 41 are positioned in place as described, these edge sections of the rims 114 and 121 are spun over the edges of the rims 111 and 118 of said brackets and gib plate for the permanent mounting of these latter members.

Although the operation of the binder is believed apparent from the foregoing description, it is herein summarized briefly.

In closed position of the binder shown in Fig. 8, the prongs 23 and 24 extend in a single plane parallel to the back 10. When the covers are opened into the plane of the back into the position shown in Figs. 2 and 5, the prong frames 14

are moved transversely apart, causing endwise movement of the prongs 23 and 24. During this self-expansion of the binder, the guide 35 is held against outward and turning movement by the engagement of the lip 60 with the detent 57, so that the prong frames 14 are held against turning movement about their pivotal mountings 17, and the prongs 23 and 24 are confined to endwise movement. At this point, it should be noted that either cover 11 may be opened independently of the other, to cause corresponding transverse movement of the respective prong frame 14 without affecting the other prong frame.

When it is desired to insert or remove a sheet, the sheet pack of the open binder is divided at the section where it is desired to insert or remove the sheet. In order to gain access to the lever 50, the sheets are divided a sufficient distance to clear the overlapping ends of the prongs 23, and the lever 50 is depressed into the position shown in Fig. 10. Since the lever is located at the center of the binder below the inner edges of the sheets A, it is accessible for operation only when the binder is open, and only after the sheets have been divided into two widely separated batches on the prongs of the respective rows. This assures against tearing of the sheets around their prong receiving apertures, caused by the accidental upward swinging of the two released prong rows apart before the separation of the sheet pack as described.

Since the lever 50 at its forward end extends across a substantial portion of the width of the back, and since the lever is accessible for operation by the separation of the sheet pack at any section above said lever, this construction permits separation of the sheet pack at that section where it is desired to remove or insert a sheet, even though said section may be near either end of the pack.

The depression of the lever 50 releases the guide 35, and permits the prongs 23 and 24 to be swung into upright position shown in Fig. 7, in which position the sheets A may be removed or inserted. In this depressed position, the forward end of the lever 50 will lie in the path of slide movement of the two flanges 98 on the slides 90, so that the open covers 11 are locked against closing. This permits the handling of the opened binder, without accidental closing of the covers, which might cause tearing of the sheets.

When the prong frames 14 are again moved into the position shown in Fig. 5 about their pivotal mountings 17, the lip 83 connected to the slide 35, sliding over the lever section 80 will cam said lever into upward position shown in Fig. 9. At the same time the lip 60 will be latched into locking position with the detent 57 as shown in Fig. 9. In this position the prongs 23 and 24 will be held in a single plane substantially parallel to the back 10, and since the flanges 98 of the slides 90 are below the lever 50, they will ride freely under said lever when the covers 11 are closed.

As many changes could be made in the above construction, and many apparently widely different embodiments of this invention could be made without departing from the scope thereof, it is intended that all matter contained in the above description or shown in the accompanying drawings shall be interpreted as illustrative and not in a limiting sense.

Having thus described our invention, what we claim as new and desire to secure by Letters Patent is:

1. A loose leaf binder comprising a pair of hinged covers, movable sheet retaining prongs, releasable means holding said prongs against movement in one direction, and means for automatically locking said covers in open position upon release of said holding means.
2. A loose leaf binder comprising a pair of hinged covers, movable sheet retaining prongs, releasable means holding said prongs against movement in one direction, means for automatically locking said covers in open position upon release of said holding means, and means for automatically releasing said locking means upon movement of said prongs in the opposite direction into a predetermined position.
3. A loose leaf binder comprising a back, a pair of covers hinged thereto, pivotally mounted sheet retaining prongs normally extending across said back, releasable means for holding said prongs in said position, and means for automatically locking said covers in open position upon release of said holding means.
4. A loose leaf binder comprising a back, a pair of covers hinged thereto, pivotally mounted sheet retaining prongs normally extending across said back, means for locking said covers in open position while said prongs are in upright position with respect to said covers, and means for automatically releasing said locking means upon return pivotal movement of said prongs to normal position.
5. A loose leaf binder comprising a back, a pair of covers hinged to said back, a pair of spaced slides connected to said covers respectively for movement towards or away from each other upon movement of said covers towards closed or open positions respectively, and a member secured to and carried by the inner side of said back and disposed between said slides in stop engagement therewith when said covers are in open position, for positively locking said covers in this position.
6. A loose leaf binder comprising a pair of hinged covers, members connected to said covers respectively, and slidable towards or away from each other upon movement of said covers towards closed or open positions respectively, and a lever lying between said members in the path of slide movement thereof in one angular position of said lever, to lock said covers in open position, and in another angular position being out of said path to permit the closing of said covers.
7. A loose leaf binder comprising a back, a pair of covers hinged thereto, sheet retaining prongs normally extending across said back, and movable into upright position with respect to said covers, means for holding said prongs in said normal position, a lever operable to release said holding means, to permit said prongs to be moved into said upright position, and means operable when said lever is in releasing position for locking said covers in open position.
8. A loose leaf binder comprising a back, a pair of covers hinged thereto, sheet retaining prongs normally extending across said back, and movable into upright position with respect to said covers, slides connected to said covers respectively, and slidable in a path towards or away from each other upon movement of said covers towards closed or open positions respectively, means for holding said prongs in said normal position, and a lever operable in one angular position to release said holding means, and simultaneously block slide movement of said slides whereby said covers are locked in open

position, said lever in another angular position being out of said path to permit closing of said covers.

9. A sheet retaining device for a loose leaf binder comprising, a pair of substantially parallel transversely movable prong bar frames, sheet retaining prongs secured to said frames, a pair of opposed slides mounted for movement with said frames respectively, and a lever, in one angular position lying between said slides in the path of slide movement thereof, to lock said slides against slide movement towards each other, and in another angular position being out of said path to permit the slide movement of said slides towards each other.

10. A sheet retaining device for a loose leaf binder comprising a pair of opposed pivotally mounted prong frames, movable towards and away from each other, sheet retaining prongs connected to said frames, means for holding said prongs substantially in a single plane during movement of said frames towards and away from each other, means for releasing said holding means to permit swinging movement of said frames, when said frames are in their furthest position apart, and means for automatically locking said frames in said latter position against movement towards each other, upon release of said holding means.

11. A sheet retaining device for a loose leaf binder comprising a pair of opposed pivotally supported prong frames, movable towards and away from each other, substantially straight sheet retaining prongs secured to said frames, and in one pivotal position of said frames extending in substantially a single plane, and in another in two separate planes, a pair of opposed slides, pivotally connected to said frames respectively, means for holding said prongs substantially in a single plane during movement of said frames towards and away from each other, and a lever for releasing said holding means to permit swinging movement of said frames and corresponding movement of said prongs into two separate planes, when said frames are in their furthest position apart, said lever in releasing position lying between said slides in the path of slide movement thereof, to lock said slides against movement towards each other, and in opposite position being out of said path to permit said latter movement.

12. A loose leaf binder comprising a non-extensible back, a pair of covers hinged to said back, a pair of opposed rows of sheet retaining prongs mounted for pivotal movement, and for substantially translatory movement towards and away from each other, and means interconnecting said two rows of prongs for correlated simultaneous pivotal movement in opposite directions.

13. A sheet retaining device for a loose leaf binder comprising a pair of substantially parallel prong bar frames, pivotally supported for swinging movement about their longitudinal axes, sheet retaining prongs secured to said frames, and means for interconnecting said frames for correlated simultaneous pivotal movement in opposite directions, and including connector bars pivotally connected to said frames respectively, and a guide member for said bars.

14. A sheet retaining device for a loose leaf binder comprising a pair of substantially parallel prong bar frames, pivotally supported for swinging movement about their longitudinal axes, sheet retaining prongs secured to said frames,

and means for interconnecting said frames for correlated simultaneous pivotal movement in opposite directions, and including connector bars, pivotally connected at their outer ends to said frames by miter hinges respectively, and a guide member for slide movement of said bars interconnecting said bars for turning movement thereof in unison.

15. A loose leaf binder comprising a non-extensible back, a pair of covers hinged to said back, a pair of opposed rows of sheet retaining prongs, mounted for pivotal movement, and for substantially translatory movement towards and away from each other, means interconnecting said two rows of prongs for correlated simultaneous pivotal movement in opposite directions, and releasable holding means engaging said interconnecting means to prevent operations thereof, whereby said prongs are held against pivotal movement.

16. A loose leaf binder comprising a non-extensible back, a pair of covers hinged to said back, a pair of opposed rows of sheet retaining prongs, mounted for pivotal movement into substantially a single plane or into two separate planes, and mounted for substantially translatory movement towards and away from each other in said single plane, means interconnecting said two rows of prongs for correlated simultaneous pivotal movement in opposite directions, and latch means engaging said interconnecting means to prevent operations thereof when said prongs are swung into single plane position.

17. A sheet retaining device for a loose leaf binder comprising a pair of substantially parallel pivotally supported elongated prong frames, transversely movable towards and away from each other, sheet retaining prongs on said frames adapted in one pivotal position of said frames to lie substantially in a single plane, and in another pivotal position to lie in two separate planes, means interconnecting said frames for correlated simultaneous pivotal movement in opposite directions, latch means engaging said interconnecting means to prevent operations thereof when said prongs are swung into a single plane position, means for releasing said latch means to permit swinging movement of said frames, and means automatically operable when said releasing means are in releasing position, for locking said frames against transverse movement towards each other.

18. A sheet retaining device for a loose leaf binder comprising two opposed rows of substantially straight sheet retaining prongs, pivotally mounted to swing in substantially a single plane or into two separate planes, and movable towards and away from each other substantially in said single plane, toggle means for holding said prongs against swinging movement during their single plane movement, and a toggle lever for releasing said holding means.

19. A loose leaf binder comprising a back, a pair of covers hinged to said back, two opposed rows of pivotally mounted sheet retaining prongs normally extending across said back, said covers being free to open and close while said prongs are in said normal position, and means for automatically locking said covers in open position when said prongs are angularly raised from said normal position.

20. A loose leaf binder comprising a substantially flat non-extensible back, a pair of substantially flat covers hinged to said back and adapted to lie substantially in the same plane as said

back in open position of said binder, a pair of opposed rows of sheet retaining prongs mounted for pivotal movement and for substantially translatory movement towards and away from each other, and means interconnecting said two rows of prongs for correlated simultaneous pivotal movement in opposite directions, said correlated movement of the prongs being effected while said back and said covers remain in substantially co-planar open relationship and while the angular relationship of said back and said covers remains unchanged.

21. A loose leaf binder comprising a non-extensible back, a pair of covers hinged thereto, two opposed rows of sheet retaining prongs normally extending in the same plane and mounted for pivotal movement with respect to said back, means guiding said prongs for endwise movement in said plane, and means for interconnecting said

two rows of prongs for correlated simultaneous pivotal movement in opposite directions with respect to said back.

22. A loose leaf binder comprising a back, a pair of covers hinged thereto, two opposed rows of sheet retaining prongs normally extending in the same plane and mounted for pivotal movement with respect to said back, means automatically responsive to the opening movement of one of said hinged covers for moving said prongs substantially endwise in said plane to afford extra space for the sheets on said prongs, and means for interconnecting said two rows of prongs for correlated simultaneous pivotal movement in opposite directions with respect to said back, while said covers are in open position.
